W. D. HAMER

METAL POLE

Filed March 19, 1926

UNITED STATES PATENT OFFICE.

WILLIAM D. HAMER, OF INDIANAPOLIS, INDIANA.

METAL POLE.

Application filed March 19, 1926. Serial No. 95,891.

The object of my invention is to produce, from commercial angle irons, an efficient post or pole—such as would be useful in supporting electric wires—and such as would offer a maximum of strength with a minimum of material.

The accompanying drawings illustrate my invention. Fig. 1 is an elevation of a pole embodying my invention. Fig. 2 a fragmentary detail in elevation. Fig. 3 a section, on a smaller scale, on line 3—3 of Fig. 2, Fig. 4 a fragmentary perspective of the lower end of one of the angle iron elements, Fig. 5 a section on the line 5—5 of Fig. 1 on a larger scale, and Fig. 6 a fragmentary elevation of another form.

In the drawings 10, 10 indicate the diverging arms of an angle iron of suitable length and transverse dimensions and preferably—as shown—an integral element, although they may be elements of a built up structure.

At various points in their lengths, the arms 10 are longitudinally slit, conveniently parallel with their sides, as at 11, to form ribbons 12 each attached at each end to the main body of the arm. Each of these ribbons at its middle 13 is then laterally displaced, away from the main body and conveniently substantially in the plane of the arm, and at the same time is twisted through an angle of 90 degrees so that the middle of the ribbon then lies spaced from the main body and at right angles to the arm from which it springs, as shown in the drawings. The middle of each ribbon is perforated to receive a clamping bolt or rivet 14.

The amount of displacement of the middles of the ribbons may be varied so as to provide a desired taper in the finished product and when four angle irons are assembled, in the manner shown in the drawings,

and the adjacent ribbons firmly connected, said ribbons serve both to connect and firmly cross-brace the angle irons and form a light but very strong pole which is equally stiffened in all directions.

Each angle iron, at its lower end, may be slit at the junction of the arms, and the ends 16 turned outwardly and perforated at 17, to form a footing.

If the base of the poles is buried these out-turned portions 16 help to anchor the pole in place and this anchorage may be readily increased by securing cross bars or plates thereto by bolts passed through the perforations 17.

In Fig. 6 the ribbons are merely displaced and overlapped.

I claim as my invention:

1. A pole formed of a plurality of angle irons the arms of each of which are longitudinally slit at longitudinally spaced apart intervals and the slitted portions laterally displaced at their middles to form a series of longitudinally spaced apart laterally extending projections on each arm and such displaced portions directly connected to the displaced portions of adjacent angle arms.

2. A pole formed of a plurality of angle irons the arms of each of which are longitudinally slit at longitudinally spaced apart intervals and the slitted portions laterally displaced and twisted at their middles to form a series of longitudinally spaced apart laterally extending projections on each arm and such displaced portions directly connected to the displaced portions of adjacent angle arms.

In witness whereof, I have hereunto set my hand at Indianapolis, Indiana, this 17th day of March, A. D. one thousand nine hundred and twenty-six.

WILLIAM D. HAMER.
